[57] CLAIM

The ornamental design for a rear view mirror mounting, substantially as shown and described.

DESCRIPTION

FIG. 1 is a side elevational view of a rear view mirror mounting embodying my new design;

FIG. 2 is a top plan view thereof;

FIG. 3 is a bottom plan view thereof;

FIG. 4 is a side elevational view thereof;

FIG. 5 is a front end elevational view thereof; and

FIG. 6 is a rear end elevational view thereof.

The broken line indications in FIG. 1 and FIG. 4 of an attached mirror and a support surface are shown for illustrative purposes only and are not part of the new design.
